UNITED STATES PATENT OFFICE.

GEORGE H. DAY, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

1,308,484.

Specification of Letters Patent. Patented July 1, 1919.

Application filed January 25, 1917. Serial No. 144,403.

To all whom it may concern:

Be it known that I, GEORGE H. DAY, a citizen of the United States, residing at Southbridge, in the county of Worcester and State of Massachusetts, have invented certain new and useful Improvements in Ophthalmic Mountings, of which the following is a specification.

My invention relates to improvements in ophthalmic mountings and has particular reference to an improved type of mounting particularly adapted for use in the industries.

One of the leading objects of the present invention is the provision of an improved construction of mounting in which the several parts shall be rigid and firm when in assembled relation, but from which the lenses may be readily detached or replaced as desired without the use of screw or other separate fastening means.

A further object of the present invention is the provision of an improved type of eye protector or like ophthalmic mounting particularly adapted for industrial purposes, in which the face engaging portion shall be entirely insulated from the metallic portion of the mounting, rendering the same less susceptible to heating action.

Another object of my invention is the provision of an improved mounting adapted to retain a plurality of lenses, and in which the front or cover lens may be readily replaced as desired without danger of breakage of the lenses therebehind or loss of parts of the mounting during the interchangement of the parts.

Other objects and advantages of my improved construction should be readily apparent by reference to the following specification taken in connection with the accompanying drawings, and it will be understood that I may make any modifications in the specific details of construction shown and described within the scope of the appended claims without departing from or exceeding the spirit of my invention.

Figure I represents a front view of my improved construction.

Fig. II represents a plan view thereof.

Fig. III represents a vertical sectional view taken as on the line III—III of Fig. I.

Fig. IV represents a similar view of a modified construction.

In the drawings, in which similar characters of reference are employed to denote corresponding parts throughout the several views, the numeral 1 is employed to denote the one piece or cylinder metal rim or frame member of my improved mounting, the opposite frame members being suitably connected as by the adjustable bridge 2 and having fitting therewithin and projecting rearwardly therefrom the shield members 3 of fiber or similar suitable material terminating in the leather or other binding portions 4, the several parts being united as by small hollow rivets providing a suitable amount of ventilation without excessive apertures which would allow entrance of dust, molten material or the like.

The said rearwardly projecting shield members 3 may be provided with suitable means for retaining the device in position on the head of the wearer, such as temples or the ordinary head band 5 here illustrated.

It is to be noted that as previously mentioned, the rims 1 are in the form of a continuous or unsplit tube whereby no exterior projections or joints are required, and are adapted to receive therebetween the rearwardly disposed protecting lens 6 and the forward or cover lens 7, which are cut of circular form to just lie within the tube referred to, if desired one or both of these lenses being provided with the spun on metallic rims 8, these rims obviating the necessity for especially edging or finishing the lenses, bracing them or rendering the particles less liable to fly, insuring a better fit or interchangeability of the several parts when used for different frames, and lessening the liability of injury to the fingers of a workman when endeavoring to himself make the desired change of lenses.

As is illustrated in the drawings, the rear lens 6 preferably rests against the forward edge of the fiber or non-metallic portion of the cup 3 which serves to limit its rearward motion, and is locked in such position as by the keeper 9 on the spring finger 10 which is suitably secured to the exterior of the frame 1 and extends inwardly through the slot 11. A second finger, or a number of fingers if desired, is placed at a suitable distance in advance of the first finger, as illustrated in Fig. III, the purpose of these fingers being to removably secure in position the cover lens 7, at the same time the thickness of the keeper 9 first referred to serving as a spac-

ing member between the lenses 6 and 7, being supplemented in its spacing action if desired by the thickness of the rims 8 so that an air space is provided tending to eliminate 5 fogging of the lenses, and in addition having a slight cushioning effect in the event of a blow sufficiently forcible to break the cover lens, reducing the liability of fracture of the rear protecting lens 6.

10 In Fig. IV, I have illustrated a slight modification of my construction in which I have shown the lower up-struck ears 12 integral with the frame member 1 in place of the lower spring fingers and keeper members, the lens in this event being slipped 15 behind one or both of the ears and then being tilted into place and suitably locked by the upper spring fingers with their keepers.

From the foregoing description taken in 20 connection with the accompanying drawings the construction of my improved frame should be readily apparent and it will be seen that I have provided a simple and efficient frame extremely ornamental in appearance, having no widely projecting parts liable 25 to catch on the clothing or the like, employing no screws or other small and delicate parts in its construction which are liable to become lost in the interchangement of the lenses, and a construction in which the face 30 of the wearer is insulated from heat by the non-metallic eye caps and non-metallic binders or face fitting portions, but with which one or more lenses may be readily inserted 35 or removed as desired, and in which the edges of the lenses are protected by supplemental cells facilitating their carrying or interchangement.

I claim:

40 1. A device of the character described including frame members having rear stops,

lenses fitting within the frames and certain of said lenses bearing against the stops, and locking devices having portions projecting into the field of the lenses for securing the lenses within the frames and retaining them in spaced relation with respect to each other. 45

2. In a device of the character described, the combination with lens-receiving rims having means for limiting the rearward movement of lenses therewithin, said rims having slots formed therethrough, of resilient fastening devices exteriorly mounted on the rims and having keeper portions extending inwardly through the slots and parallel 50 to the plane of the lenses for removably securing the lenses within the rims and retaining them in spaced relation with respect to each other. 55

3. In a device of the character described, the combination with a lens frame having a plurality of circumferentially extending slots formed therein of spring fingers secured to the outer face of the frame and having angular keeper portions, one wing of 60 each of said keeper portions depending through the slots in spaced relation and the other wing bearing against the outer face of 65 the lens frame whereby the fingers may be sprung outward to facilitate the insertion of 70 a lens within the frame, and when sprung inward the keeper portions will engage opposite faces of the lens to lock it against either forward or rearward movement within the frame. 75

In testimony whereof I affix my signature in the presence of two witnesses.

GEORGE H. DAY.

Witnesses:

HAROLD K. PARSONS,
E. M. HALVORSEN.
